CLAIM

The ornamental design for an e-cigarette case, as shown and described.

DESCRIPTION

FIG. 1 is a perspective view of the e-cigarette case of the instant invention in a closed position;

FIG. 2 is a front side view thereof;

FIG. 3 is a rear side view thereof depicting two exhaust apertures;

FIG. 4 is a right side view thereof;

FIG. 5 is a left side view thereof;

FIG. 6 is a top view thereof;

FIG. 7 is a bottom view thereof

FIG. 8 is a perspective view of said e-cigarette case in an open position depicting an e-cigarette retainer section on the left side and a packet on the right side;

FIG. 9 is a right side of FIG. 8;

FIG. 10 is a left side of FIG. 8;

FIG. 11 is a front end of FIG. 8;

FIG. 12 is a rear end view of FIG. 8;

FIG. 13 is a top plane view of FIG. 8 depicting said exhaust apertures; and,

FIG. 14 is a bottom plane view of FIG. 8.

The portions of the e-cigarette case illustrated in broken lines form no part of the claim for the e-cigarette case.
